US0D1085139S

(12) **United States Design Patent** (10) **Patent No.:** **US D1,085,139 S**
(45) **Date of Patent:** **** Jul. 22, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Alan C. Dye**, San Francisco, CA (US); **Behkish Johnnie Manzari**, San Francisco, CA (US); **Grant R. Paul**, San Francisco, CA (US); **William A. Sorrentino, III**, San Francisco, CA (US); **Andre Souza Dos Santos**, San Jose, CA (US)

(73) Assignee: **Apple Inc.**, Cupertino, CA (US)

(**) Term: **15 Years**

(21) Appl. No.: **29/943,919**

(22) Filed: **May 24, 2024**

Related U.S. Application Data

(63) Continuation of application No. 29/852,133, filed on Sep. 2, 2022, now Pat. No. Des. 1,029,030, which is a continuation of application No. 29/831,524, filed on Mar. 21, 2022, now Pat. No. Des. 962,977, which is a continuation of application No. 29/798,978, filed on Jul. 12, 2021, now Pat. No. Des. 949,190, which is a continuation of application No. 29/705,050, filed on Sep. 9, 2019, now Pat. No. Des. 924,912.

(57)

CLAIM

The ornamental design for a display screen or portion thereof with graphical user interface as shown and described.

DESCRIPTION

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.

1 Claim, 1 Drawing Sheet
